SNOW REMOVAL APPARATUS

Floyd John Robarge, Gloversville, N. Y., assignor
of one-half to Paul Prevot, Gloversville, N. Y.

Application March 7, 1939, Serial No. 260,448

9 Claims. (Cl. 37—43)

This invention relates to a snow removing apparatus, and more particularly to a novel machine for use in removing snow from sidewalks and driveways.

5 One of the objects of the invention is to provide a snow removing apparatus of the type employing a rotary fan wheel combined with a rotary brush which will sweep clean to the surface of the walk and force the swept snow into a position where it 10 may be picked up by the fan wheel and discharged from the machine.

Another object is to supply a snow removal apparatus of the above character in which the rotary brush is yieldingly mounted so that it may conform to the ground surface and yet always tend to move bodily toward said surface.

15 With the foregoing objects outlined and with other objects in view which will appear as the description proceeds, the invention consists in the 20 novel features hereafter described in detail, illustrated in the accompanying drawing, and more particularly pointed out in the appended claims.

In the drawing:

Fig. 1 is a front elevation of a portion of a snow 25 removal apparatus provided with my improvements.

Fig. 2 is a side elevation of the same.

Referring to the drawing in detail, 3 designates the frame of the apparatus which is mounted on 30 wheels, the front wheels 4 being illustrated and the rear wheels not shown.

The front end of the shaft 5 extends into a casing 6 having a transversely extending closed rear wall 7 supporting a bearing 8 in which the shaft 35 is journaled.

The casing is open at the bottom and provided with combined side and top walls 9 of substantially inverted U-shape. A front wall 10 of inverted U-shape has its outer edge secured to the 40 wall 9 in a plane arranged about midway between the front and rear edges of the wall 9, and owing to the skeleton formation of the front wall, snow may travel into the casing where it will be acted upon by a fan wheel 11 fixed to the front end portion of the shaft 5. The fan wheel preferably 45 consists of a disc 12 having radial blades 13 fixed to its front surface, and such wheel rotates in the chamber between the front and rear walls 9 and 7 respectively.

50 The wall 9 projects forwardly from the front wall 10 in the form of an inverted U-shaped hood 14 that is adapted to guide snow into the casing 6.

Snow cutting blades 15 are fixed to the forward end of the shaft and incline forwardly and outwardly from the front end of the shaft, so that

the tips of the blades will travel in a path adjacent to the front edge of the hood 14.

A discharge chute 16 extends laterally from the top portion of the casing for the purpose of directing the snow to one side of the machine as the snow is removed.

Immediately to the rear of the casing 6, the frame is provided with depending brackets 17 which pivotally support the medial portions of levers 18, the front ends of which form journals 19 for the shaft 18 of a horizontally disposed cylindrical brush 20 arranged immediately behind the lower edge of the rear wall of the casing. The brush is driven in a clockwise direction by the following means. A bevel gear 21 fixed to the 15 shaft 5 drives a bevel gear 22 fixed to the inner end of a counter-shaft 23 which may be rotatably supported in brackets 24 fixed to the rear wall of the casing. A sprocket wheel 25 fixed to the outer end of the counter-shaft, drives a sprocket 20 chain 26 which in turn drives a sprocket wheel 27 fixed to the brush shaft 18.

For the purpose of yieldingly holding the brush in contact with the surface to be cleaned, the rear end of each lever 18 is connected by a coil spring 25 to the frame 3.

A transversely extending hood 28 projects from the rear wall of the casing over and downwardly at the rear of the brush so as to compel snow swept by the brush to move forwardly into a position where it may be reached and lifted by the paddles 13 of the wheel 12.

In operation, the engine will drive the shaft 5 in a clockwise direction so that the blades 15 will cut the snow as the machine travels forward. 35 The snow disturbed by the blades will enter the casing 6 and come in contact with the paddles 13 which will lift the same and force it out through the chute 16. As the machine travels forward, the cylindrical brush 20 will sweep the surface 40 snow into a position where it may also be lifted by the paddles and thrown from the machine.

From the foregoing it is believed that the construction, operation and advantages of my invention may be readily understood, and I am aware 45 that changes may be made in the details disclosed, without departing from the spirit of the invention, as expressed in the claims.

What I claim and desire to secure by Letters Patent is:

1. In a snow removing apparatus, a casing having an open front, an open bottom and a discharge chute, a rotary paddle wheel arranged in the casing and adapted to convey snow entering the front of the casing and to discharge the 55

- same through said chute, and a rotary brush positioned at the bottom portion of the casing and arranged to sweep snow into the casing through the open bottom of the same.
5. In a snow removing apparatus, a casing having an open front, an open bottom and a discharge chute, a rotary paddle wheel arranged in the casing and adapted to convey snow entering the front of the casing and to discharge the same through said chute, a rotary brush positioned at 10 the bottom portion of the casing and arranged to sweep snow into the casing through the open bottom of the same, and means for yieldingly urging the brush bodily downward.
15. 3. In a snow removing apparatus, a casing having an open front and a discharge chute, a rotary paddle wheel arranged in the casing and adapted to convey snow entering the front of the casing and to discharge the same through said chute, a rotary brush arranged at the bottom portion 20 of the casing and adapted to sweep snow toward the casing, and a hood for the brush extending rearwardly from the casing over the brush and downwardly at the rear of the same.
25. 4. A snow removing apparatus of the character described, comprising a wheel supported frame, a casing arranged at the front end of the frame and having an open front, an open bottom and a lateral discharge chute, a driven shaft extending into the casing, a paddle wheel fixed to the shaft and operating in the casing, a substantially cylindrical rotary brush arranged at the rear of the casing immediately behind the open bottom of the same, and means for driving said brush from the shaft to cause the brush to sweep snow toward the open bottom of the casing.
30. 5. A snow removing apparatus of the character described, comprising a wheel supported frame, a casing arranged at the front end of the frame and having an open front, an open bottom and a lateral discharge chute, a driven shaft extending into the casing, a paddle wheel fixed to the shaft and operating in the casing, a substantially cylindrical rotary brush arranged at the 35 rear of the casing immediately behind the open bottom of the same, means for driving said brush from the shaft to cause the brush to sweep snow toward the open bottom of the casing, and a hood projecting from the casing rearwardly over and downwardly of the rear portion of the brush.
40. 6. A snow removing apparatus of the character described, comprising a wheel supported frame, a casing arranged at the front end of the frame and having an open front, an open bottom and a lateral discharge chute, a driven shaft extending into the casing, a paddle wheel fixed to the shaft and operating in the casing, a substantially cylindrical rotary brush arranged at the 45 rear of the casing immediately behind the open bottom of the same, means for driving said brush from the shaft to cause the brush to sweep snow toward the open bottom of the casing, and means including a spring for yieldingly urging the brush downwardly.
50. 7. In a snow removing apparatus, a wheel supported frame, a casing arranged at the forward end of said frame, said casing comprising a rear 55 wall, combined side and top walls of substantially inverted U-shape, and a front wall of substantially inverted U-shape, the outer edge of the front wall being secured to the combined side and top walls along a transverse vertical plane arranged substantially midway between the front and rear edges of the combined side and top walls, a horizontally disposed driven shaft extending through the central portion of the rear wall, a paddle wheel fixed to the shaft and rotatable in the casing, cutting blades fixed to the front end of the shaft and having their tips arranged to travel in a path positioned at the front edge portion of said combined side and top walls, a substantially cylindrical brush extending across the casing immediately at the rear of the lower edge of the rear wall of the casing, and means for rotating the brush from said shaft.

60. 8. In a snow removing apparatus, a wheel supported frame, a casing arranged at the forward end of said frame, said casing comprising a rear wall, combined side and top walls of substantially inverted U-shape, and a front wall of substantially inverted U-shape, the outer edge of the front wall being secured to the combined side and top walls along a transverse vertical plane arranged substantially midway between the front and rear edges of the combined side and top walls, a horizontally disposed driven shaft extending through the central portion of the rear wall, a paddle wheel fixed to the shaft and rotatable in the casing, cutting blades fixed to the front end of the shaft and having their tips arranged to travel in a path positioned at the front edge portion of said combined side and top walls, a substantially cylindrical brush extending across the casing immediately at the rear of the lower edge of the rear wall of the casing, and means for rotating the brush from said shaft.

65. 9. In a snow removing apparatus, a wheel supported frame, a casing arranged at the forward end of said frame, said casing comprising a rear wall, combined side and top walls of substantially inverted U-shape, and a front wall of substantially inverted U-shape, the outer edge of the front wall being secured to the combined side and top walls along a transverse vertical plane arranged substantially midway between the front and rear edges of the combined side and top walls, a horizontally disposed driven shaft extending through the central portion of the rear wall, a paddle wheel fixed to the shaft and rotatable in the casing, cutting blades fixed to the front end of the shaft and having their tips arranged to travel in a path positioned at the front edge portion of said combined side and top walls, a substantially cylindrical brush extending across the casing immediately at the rear of the lower edge of the rear wall of the casing, means for rotating the brush from said shaft, and a hood extending rearwardly and downwardly from the casing and projecting over and downwardly at the rear of said brush.

FLOYD JOHN ROBARGE.
